ELECTRICAL COMMUNICATION SYSTEM

Harold F. Elliott, Palo Alto, Calif.

Application May 29, 1936, Serial No. 82,494

4 Claims. (Cl. 250--20)

The inventions described in this application and in my pending application Serial No. 82,495 filed May 29, 1936, pertain to Electrical communications and multiple function control clocks. The methods and apparatus described and claimed in these applications are not limited to the usages chosen for illustration but are useful in a wide variety of fields as will be evident to those skilled in mechanical and electrical arts.

For the purpose of illustrating principles and methods I have chosen for description herein electrical communications and receiving systems such as may be used for receiving intelligence by wire or radio in the form of speech, vision, facsimile or other signaling methods. It will be understood that I do not limit myself to the examples or applications chosen for illustration, but claim broadly the inventions set forth in the claims of this and the aforesaid copending application. As applied to receivers for home entertainment, my system has the advantages of permitting scheduled programs to be received automatically at predetermined hours by simple pre-setting means. It also has the further advantage of using precisely pre-tuned circuits which relieve the operator of the tuning operation required in existing methods. The pretuned circuits assure improved quality of reception since errors in tuning resulting from carelessness or lack of operative skill are avoided. Each of the selected channels may be pretuned for optimum results commensurate with the prevailing conditions. For example: a distant station may have sharp tuning for selectivity while a nearby station may have broad band-pass tuning for improved quality. The various channels may be adapted to varied purposes, for example; there may be provided several channels for reception over wires, several others for long wave radio, others for short wave radio, television or facsimile. Other settings may provide for the operation of household appliances, lighting the furnace, ringing a bell, turning on a percolator or regulating an oven by a schedule. The many advantages and possibilities can best be grasped by referring to the attached drawings showing several preferred forms and illustrative examples of applications.

Referring to the accompanying drawings in which like numerals of reference indicate similar parts throughout the several views;

Figure 1 shows in outline the circuits of an electrical communication receiving set embodying the methods, apparatus and principles of my inventions; Figures 2 and 3 show an elevation, and details of the receiver of Fig. 1; Fig-

ures 4 and 5 show an alternative arrangement of details; Figure 6 shows a partial view and certain details of another receiver suitable for use with my system; Figures 7-12 inclusive show partial sections and elevation of the same; Figures 13 and 14 show partial assemblies and sections of still another receiver. Figs. 15-19 show modifications of the system shown in Fig. 1.

Radio and wire line receiving circuits may be applied to any of these assemblies and the type of circuit may be any suitable to the purpose. Examples of circuits involving both superheterodyne and tuned radio frequency methods for radio, wire line, voice or other reception are illustrated in the circuit diagrams of which Figure 1 shows a tuned radio frequency receiving circuit embodying the principles and methods of my inventions, and Fig. 15 which, for lack of space, is continued in Fig. 16, shows circuits combining the two so that the advantages of each are obtained. Figure 1 and Figure 17 show two relay control circuits utilizing two methods of control; Figure 18 shows an application of my system to a receiver having motor operated controls; Figure 19 illustrates a timing and control system having several stations.

In the specific embodiments of the invention illustrated in said drawings, reference will be made initially to Figure 1, wherein is shown, in diagrammatic form, the controls and circuits of a radio receiver embodying my system and utilizing the multiple function control clock described in my copending application Serial No. 82,495 filed May 29, 1936, to which reference is made for constructional details thereof. This is one of the important fields of application of this clock and has been chosen here as an example to illustrate one method of its use. Briefly the system of Figure 1 comprises a radio receiver having a relay controlled channel selecting system arranged for automatic operation under clock control and also for manual operation under push button control. Numerals 1 to 11 inclusive indicate diagrammatically a plurality of "station" or channel busses, while one of a plurality of "time" busses is indicated by numeral 12. The busses of each set are preferably parallel, and one set is perpendicular to the other, but without direct contact, thus giving the criss-cross appearance of the busses of the two sets. Interconnection between any one bus of one set with any one bus of the other set may be accomplished by an interconnector such as is indicated at 13. There are as many interconnectors as there are busses in one set, that is, the 55

number of busses in the set of busses upon which the interconnectors are slidable determines the number of interconnectors provided. Diagrammatically indicated at 14 and 15 are control means by which the interconnectors may be moved individually to selected interconnecting positions by members 16 and 17. Control means 15 comprises a finger index dial somewhat like the dial of an automatic telephone. In the normal or unset position the interconnectors 13 are all slid to a place where they will overlie bus 11, which as shown but not necessarily, is a neutral or inactive bus merely affording a position of rest for the interconnectors. As between the time busses such as 12 on which the interconnectors slide and members 14, 15, 16 and 17 which actuate the interconnectors, there is a relative movement. Member 17 may be moved longitudinally of itself by means of time dial 14 and member 18 and thus projection 18 upon member 11 may be brought opposite any one of the interconnectors, or, conversely said member may be longitudinally stationary and the bank or set of time busses may be moved laterally to obtain the relative positioning with any one bus opposite the projection. After projection 18 is positioned opposite the selected interconnector, member 17 is moved transversely of itself and longitudinally of the set of time busses, sliding interconnector 13 down to the desired cross bus of the other set such as "station" bus 3 illustrated. As stated, member 14 is a time index dial which serves through control means 19 to move projection 18 to a selected time bus. The finger index dial 15 then serves by clockwise rotation to move the interconnector, as 13, associated with that time bus to a selected station bus, as 3. Member 20, actuated through member 16 by counterclockwise rotation of dial 15 serves to return all interconnectors to neutral bus 11. Reference is made to my aforementioned copending application Serial No. 82,495, filed May 29, 1936, for mechanical arrangement and constructional details of these parts. As set forth in detail therein, time dial 14 preferably takes the form of a rotatable ring having ninety-six notches, one for each quarter hour of the twenty-four hours of a day. This ring is preferably indexed or graduated in quarter hour intervals. Member 17 is preferably a ring of insulating material having a projection 18 arranged to engage any individual interconnector, as 13. Rotation of dial 14 rotates ring 17 through the medium of a pin or other linkage 19, thus bringing projection 18 opposite any selected interconnector. When projection 18 has been positioned opposite the interconnector corresponding to the selected quarter hour, this interconnector may then be moved to the desired station bus, as 3, by rotation of dial 15. This is preferably brought about through the medium of a cam or lead screw, or other suitable linkage diagrammatically shown at 16 in Fig. 1. This linkage serves to translate rotary motion of dial 15 into transverse motion of ring 17, and projection 18. As set forth in detail in my co-pending application S. N. 82,495, filed May 29, 1936, the time busses, as 12, preferably take the form of a series of rods arranged in cylindrical formation around the axis of dials 14 and 15, parallel with this axis, while the station busses, 1 to 11, preferably take the form of a set of conducting rings concentric with the same axis, which is also the axis of ring 17. Member 20 is preferably a second insulating ring having the same

axis, and arranged so that reverse rotation of dial 15 causes linkage 16 to move ring 20 along its axis, engaging all interconnectors and returning all to neutral bus 11.

The receiver shown in Figure 1 is of the tuned radio frequency type, having two radio frequency amplifier stages 21 and 22 succeeded by a governor 23-24, a compensator and volume control stage 25, a demodulator 26, an audio frequency amplifier 27 with phase reverser 28 and 10 feeding power output tubes 29 and 30. The input to the first stage 21 includes an input transformer 31, which is tuned to select desired program channels by adjustable capacitors 32-33-34 etc. which are connected into the circuit by 15 relay contacts 35, 36, 37, etc. of which relay contact 36 is shown actuated into circuit closing position. The input circuits of stages 22, 25 and demodulator 26 are similarly arranged with adjustable capacitors and relay contacts, identified 20 by similar reference numerals but with the addition of exponents. Relay contacts 36 and the corresponding contacts identified by numeral 36 with exponents in succeeding stages are closed in unison by a relay armature, shown at 38, through 25 the medium of a common control member 38A (indicated by dotted line in Figure 1). Once closed, the associated group of contacts are held closed by a latch, or interlock 39. Suitable mechanism for these parts will be described 30 more in detail in several forms hereinafter. A trip mechanism, indicated at 40, opens previously latched relays whenever a shift is made from one channel to another and also whenever an "off" signal is given by the clock or by the push buttons which are indicated at 41. In Figure 1, the relay contacts associated with channel 2 are shown closed, tuning all circuits for this channel. Channel 1 is indicated as a variable channel whose tuning may be changed to receive a range 40 of radio stations by turning dial 42. Channels 2, 3, et sequel through 9, illustrate channels having tuning means which are pre-adjusted and then left fixed for the reception of definite stations. Additional channels are omitted for sake 45 of simplicity in the circuit diagram, but may be similar to those shown or take other suitable form. It will be obvious that the relays may be arranged in a great variety of ways to serve many purposes. For example, one variable and 50 three fixed channels may be provided for reception of radio broadcast programs, three other channels may be provided for reception of programs over wire lines at audio or carrier frequency, another may provide for television, another for facsimile or news service and so on for as many channels as desired to include in the apparatus. Each channel may have the construction and response characteristics best suited to the purpose thereof. The relays may also 55 be used to control the household furnace, range or other appliances.

In the arrangement illustrated in Figure 1, the control impulses which operate the various relays are of short duration and are routed from 65 source 45 through bus 48, clock contact arms 46 and 47 to the time busses, as 12, thence through the interconnectors, as 13, to the station bus, as 3, contacted by said interconnector, thence to the relay operating coils, as 43, and trip coil 44 70 back to the source of control current 45. This source is indicated at 45 as comprising a step down transformer, copper oxide rectifier and storage capacitor. The relays may also be operated manually by the push buttons indicated 75

at 41. In the arrangement shown in Figure 1, contact arm 46 is driven with the minute hand of the clock and makes a contact of brief duration at 15 minute intervals with bus 48. Arm 5 47 is driven with the hour hand and distributes the impulse from arm 46 to the time bus, as 12, corresponding to the particular 15 minute interval. The interconnectors, as 13, may be set for any desired schedule of programs, or other functions 10 by use of the time index and station dials shown schematically at 14 and 15 to which reference has been made. As described in detail in my copending application it is only necessary to set time index 14 at the desired quarter hour 15 and then to dial the desired station on dial 15 in order to make the interconnection necessary to bring in that station at that time. With a 24 hour clock and 96 time busses arranged at quarter hour intervals, a change of programs may be 20 had every 15 minutes if desired. In the arrangement of busses shown in Figure 1, "station" bus 1, is an "off" bus and serves to energize the trip coil 44 whenever it is desired to turn the receiver off either by the clock or by the push buttons.

25 Rheostats for volume and tone control are shown at 49 and 50. A set of contacts indicated at 51, operated in conjunction with the tuning relay contacts, as 36, 36', etc. as indicated by common control 38A, serves to close contactor 30 52 and energizes the power supply circuits whenever any of the program relays are closed. Signal lamps, as indicated at 53, may be included to show which channel is in operation if desired. Interlock contacts 54 may be operated in conjunction with the power relay for opening the 35 circuit of the "off" bus, 1, if desired. This refinement prevents the trip relay 48 from "clicking" in case the clock passes "off" impulses when the set has already been turned off. A further 40 refinement which may be desirable in some cases comprises a set of interlock contacts introduced in series with the relay closing coils, such as 43, as indicated by crosses, as at 55. As described hereinafter in connection with Figures 2 and 7 45 these contacts are preferably arranged to open after the associated relay has been latched closed, thereby opening the operating circuit of that relay. This refinement prevents the relay drawing current or "clicking" after it has been 50 closed.

In order to cushion surges in the amplifier and speakers when a shift of channels is made, a set 55 of interlock contacts, as indicated at 56, is provided. These contacts cause the automatic gain control bus to receive a negative charge from rectifier 57 whenever any of the relays are in process of opening or closing. The gain of stages 21, 22 and 25 is thus momentarily reduced causing one station to "fade" out and the other to "fade" in. As described in greater detail herein- 60 after in connection with Figures 2, 4 and 7, the construction of "fading" relay contacts, as 56, is such that a circuit is momentarily closed from bus 56A to 56B whenever any of the channel 65 selecting relays is in the process of opening or closing.

It will be obvious that a great variety of means 70 may be conceived for carrying out the various functions illustrated and described above. When used with the multiple function control clock described in my copending application Serial No. 82,495 filed May 29, 1936, to which reference has been made, a receiver possessing many highly desirable features is obtained. Broadcasting, al- 75 though a relatively new art, has already settled

quite definitely into schedules and channels. By means of the time and station dials any desired schedule of programs may be set up for the succeeding 24 hour period. Alternative selections may be made via the push button controls at any 5 time, the push button being effective only for the one period then in progress and the clock resuming control whenever a previously set schedule is encountered as the clock rotates. The use of relays operated by impulses of short duration and 10 held by mechanical interlocks has several advantages. The clock and push button controls may be connected directly in parallel without interference and the relay coils may be designed for intermittent service. Additional control 15 units as described in connection with Fig. 19 may readily be provided if desired.

Several methods of arranging the receiving circuit, relays, tuning capacitors, coils and other elements for use with circuits of the type shown 20 in Figures 1, 15 and 16 will now be described.

Referring to Figure 2 the receiver here illustrated includes a plurality of shield cans as 58 housing electrical circuit tuning apparatus, a plurality of switches of which 59, 60, 61 and 62 25 are examples, a plurality of relay mechanisms for operating the switches of which 63, 64 and 65 are examples. A suitable base plate, electronic tubes, transformers, capacitors, inductors and the like are of course provided but will not be 30 enumerated in detail here for the sake of simplicity. The arrangement of tubes, tuning apparatus, switches and relays is such that each amplifier stage may be connected with any one of a plurality of circuit tuning elements by the action 35 of the relays. The relays are in turn arranged so that the operation of any one relay brings into action a coordinated set of circuit elements specifically adapted to the purpose to which the relay is devoted, as for example an entertainment 40 program via a wire line, or via radio, or a television program via short wave radio.

In the arrangement shown in Figure 2 each relay 45 comprises a rotary shaft, as 66, carrying rotary switches as 67 and 68, operated by electromagnets such as are shown at 69 and armatures such as 70 and 71. The armature is shown in open position at 70 and in closed position at 71, being held closed by latch 72. Each amplifier stage may be provided with one or more busses 50 as 13, through which connections may be made to the tuning elements associated with that stage, via the switches. The busses and switches for each stage may be grouped in suitable shielded compartments as indicated at 73A. The shaft 55 of each relay, as 66, may carry as many sets of contacts as required to perform the switching operations necessary to connect and tune the channel associated with that relay. The contacts may be constructed in a great variety of ways 60 depending upon the service to be performed, production methods, etc. The arrangements shown at 59 and 60 provide double break connections from the bus 73 to the tuning elements such as are shown in shield 58. The switches, busses 65 and tuning elements are thus completely isolated when the switches are open, avoiding capacity effects and interactions between circuits. A switch such as is shown at 62 may be used where a single break with nominal stray capacity coupling is satisfactory. The switch shown at 61 provides for momentary connections between busses 83 and 84 in the "fader" circuit discussed further below.

The relay arrangement shown in Figure 2 in- 75

cludes a mechanical interlocking system which provides for holding the relays closed after they have been set by electrical impulses of short duration. When the operating coils of any relay are energized the switches attached to that relay are closed and locked and all other relays are opened automatically. This is arranged by providing each relay with a latch, as illustrated at 12 for relay 64 which is shown closed, and at 13 for relay 65 which is shown open. Release relay 74 is mechanically connected with the latches of all relays through release bar 75. A trip mechanism 76 interconnects release relay 74 and release bar 75 in such a way that an impulse to relay 74 moves the bar 75 to the left thereby tripping all relay latches and then immediately permits bar 75 to return to its original position. The release relay 74 comprises two electromagnets 74A and 74B and an armature 74C which is pivoted to rotate on pin 74D. A trip arm 74E is attached to the armature and rotates with it about pin 74D as an axis. Spring 74F holds the rotating elements in the position illustrated against the stop 74G when the magnets are not energized. When current is applied to electromagnets 74A and 74B armature 74C rotates clockwise, carrying with it trip arm 74E. The outer end of the trip arm 74E engages with latch 76 which is attached to the bar 75 through the pivot 76A. Bar 75 is pulled to the left, as viewed in Fig. 2, by the rotation of the trip arm 74E about the pivot 74D. The outer end of the trip arm 74E swings in an arc about the pivot 74D as shown by the dotted line 74H. Due to this curvature, after a few degrees of rotation, the outer tip of arm 74E slides from the outer tip of latch 76 to disengage the two members. Spring 76B then pulls bar 75 to the right against the stop 75A. Bar 75 may slide in grooves or may be suspended on rotatable arms as 75B. When the magnets 74A and 74B are de-energized, spring 74F pulls trip arm 74E back to the position illustrated in Fig. 2. Latch arm 76 which is pivoted to bar 75 at 76A is pushed out of the way by the tip of arm 74E as it passes. After this the spring 76B pulls the latch 76 back against the stop 76C to the position illustrated in Fig. 2 and trip arm 74E and the latch 76 are in position for another cycle of operation. This permits any main relay, as 64, simultaneously or thereafter energized, to be latched shut as shown accomplished with respect to latch 72. Any relay not energized will be left open, as is the case with respect to relay 65. It is thus possible to set any relay, and release any previously set relay by a single impulse of short duration. To this end, the operating coils of the release relay 74 may be connected in a return circuit common to the operating coils of all relays as shown at 44 in Figure 1. Release relay 74 then operates whenever any of the setting relays are actuated. All relays may be opened by routing an impulse through the coils of release relay 74, separately. In the circuits of Figure 1, bus 1 is allocated to this service, being an "off" bus.

The circuit tuning elements may be of any type suitable to the function to be performed. In some instances each tube may have a single tuning inductor and a plurality of adjustable tuning capacitors which may be connected successively to the inductor by the relays for tuning in various channels or stations. This is the arrangement indicated in Figure 1. In other instances a plurality of tunable circuits, each complete in itself, may be provided. The circuits

may be arranged singly or in coupled pairs with or without band pass characteristics. If circuits in coupled pairs are used the coupling and damping may, if desired, be adjustable so that the response characteristics may be adjusted to the specific conditions of operation of that channel. An arrangement especially well suited to the latter system is set forth in my copending application S. N. 741,139 of Aug. 23, 1934, and one pair of circuits embodying features disclosed and claimed therein is illustrated in the present disclosure as the circuit tuning means within the shield cans at 58 in Figure 2. Inductors 77 and 78 are movable relative to one another and relative to damping ring 79 by means of knob 80. Each inductor has its adjustable tuning capacitor illustrated at 81 and 82. Other methods discussed in this application may also be applied; for example band pass action may be obtained in any set of circuits by staggering the tuning of the element comprising the amplifier stages thereof, introducing damping if required by use of either fixed or variable resistors, either in series or in shunt with tuning elements. Examples of this are discussed further in connection with the circuit diagrams, Figures 16 and 15.

A switch suitable for operating the "fading" or biasing arrangement indicated at 56 in Figure 1 is shown at 84 in Figure 2. Busses 83 and 84 (Figure 2) are momentarily connected together whenever the shaft is rotated either to open or close the switches thereon. This is accomplished by proportioning the switch elements so that switch contact 84A (Fig. 2) closes before contact 84B opens, and vice versa.

Figure 3 shows a cut away plan view of the switches of the type described in connection with Figure 2, like numerals of reference indicating like parts.

Figures 4 and 5 show an alternative arrangement for switches and tuning apparatus adapted for use with circuits and relays of the type shown in Figures 1 and 2. Examples of switches in closed and open position are shown at 85 and 86. Each switch has its associated adjustable tuning capacitors, illustrated at 87 and 88. A flexible bus as 89, connects each group of switches with its associated inductor system, outlined at 90 and corresponding amplifier tube, as illustrated. Suitable shielded compartments, as 91 and 92 are provided for the busses and tuning elements associated with each amplifier stage. To reduce manufacturing costs, associated tuning elements, as capacitors 87 and 88 may be assembled in groups on a suitable base, as 93. The stud carrying the adjusting nut of the capacitor may extend to form one side of the switch, as shown at 94, (see Figure 5). Each relay may be provided with switches for energizing the power supply system of the receiver either directly or through a power relay, as indicated at 92 in Figure 1. Each relay may also carry a switch or switches for cutting off the speakers, or for reducing the output or gain during switching operations in order to avoid objectionable noises or other disturbances due to switching. An example of one suitable form of switch for this purpose is shown at 95 which is proportioned so that contacts 95A close before contacts 95B open, and vice versa, thus energizing a "fading" or biasing circuit as illustrated at 56 in Figure 1.

For circuit arrangements wherein it is desired to open the control circuit of a given relay after it has been closed and latched, interlock contacts associated with the latches, as indicated at 96

and 97 in Figure 2 may be used. Such contacts are useful when the clock or push button mechanism is such that the control circuit is continually energized. Such contacts may also be inserted in series in the control circuit as indicated at 55 in Figure 1 to avoid "clicking" when an impulse is sent to a relay already closed.

The tuning elements and relays of a radio receiver especially well suited to circuits of the type discussed in connection with Figures 1, 15 and 16 are shown in Figure 6 and associated partial elevational and sectional views 7 to 12 inclusive. Numerals 98 and 99 (Figure 6) indicate two of a plurality of relays which are used for making the connections necessary to tune the receiver for various channels or stations. Four banks of adjustable tuning capacitors are indicated at 100 to 103 inclusive. Each relay as 99 comprises an electromagnet, as shown at 104 Figure 7, and an armature, 105, which serve to operate a plurality of contacts through the medium of an insulating tie bar, see 106 in Figure 7. This figure is a section along line 7—7 of Figure 6 taken so as to show in elevation the operating mechanism and contacts of relay 99, which is shown here in closed position. Four sets of contacts, 107, 108, 109 and 110 are provided for connecting into tuned circuits the tuning capacitors as 100, 101, 102 and 103, associated with the channel or station assigned to this particular relay. The transformers of the amplifier stages whose circuits are thus tuned may be housed in suitable shields as indicated at 111, Figure 6, and a bank of amplifier tubes may be placed adjacent thereto as indicated at 112. The switches and capacitors associated with each stage may be housed in a shielded compartment as indicated at 113, Figures 6 and 7. A stationary insulating bar 114, Figures 6 and 7, may be provided for holding the "stationary" contacts in the required positions, cooperating with the insulated tie rod, 106, Figures 6 and 7, which serves for actuating the "moving" contacts of the several switches. Further details of these contacts, rods, and bars are shown in Figure 12 representing a perspective view of contacts 110 and associated tie rod 106 and bar 114.

Each switch, as 110, (Figs. 6, 7, and 12), comprises two spring leaves as 110A and 110B which carry contacts as 110C and 110D. Spring leaf 110A is dovetailed into the insulating tie rod 106 as illustrated at 110E in Fig. 12. Spring leaf 110A therefore moves with rod 106 whenever the latter is actuated by armature 105 (Fig. 7). Armature 105 is pivoted at 105A. Energization of the electromagnet 104 attracts armature 105 to the magnet and shifts the bar 106 to the left as shown in Fig. 7. This moves all of the switch leaves 110A which are dovetailed to the bar 106 to the left and closes all of the associated contacts as 110C and 110D thereby connecting into the circuit the tuning elements controlled by these switches. Latch 118 engages the armature 105 and holds the switches closed after the magnet is de-energized. When the latch 118 is tipped, as described hereinafter, the spring leaves 110A of the switches pull tie bar 106 to the right until the armature 105 rests against the stop 105B. In order that this motion may open the contacts as 110C and 110D, spring leaf 110B is provided with a projection 110F which engages with a fixed stop 114B. This stop is formed by a notch 114A in the stationary insulating bar 114 (Fig. 12). Leaf 110B is free to move to the left when leaf 110A moves to the left for bringing contacts 110C and 110D into closed position. When leaf 110A

moves to the right, the motion of leaf 110B is limited by the projection 110F engaging the stop 114B. The notch 114A thus positions leaf 110B so that motion of the tie bar 106 may open and close contacts 110C and 110D. The pressure applied to the contacts is determined by the tension of the spring leaf 110B, and this pressure is applied to the contacts the moment they are closed, being approximately the same as the pressure exerted by spring leaf 110B against stop 114B. The notched bar 114 therefore serves to determine the position of its associated spring leaves as 110B, and the construction permits definite contact pressures to be maintained as well as definite positions. The construction also permits the moving switch elements as spring leaf 110A to serve as the spring for actuating armature 105 pulling it away from the magnet 104 when de-energized. The dovetail and notch construction of insulating bars 106 and 114 permits the use of low cost stampings and this construction likewise facilitates the assembly of the multiple switch parts.

In addition to the switches for performing tuning operations, each relay may carry as many auxiliary switches as needed. In Figures 6 and 7, a three element auxiliary switch 115 is provided for operating the biasing circuits which provide for "fading" to give quiet operation during the shift from one channel to another as discussed in connection with switch 56, Figure 1. A second auxiliary switch 116 serves to energize the power supply contactor, and light a signal lamp if desired, as shown at 51, 52 and 53 in Figure 1. A third set of auxiliary contacts indicated at 117 may be arranged to function in cooperation with the latch 118, Figure 6, providing means for opening the control circuit of the relay after it is latched closed, as indicated at 55, Figure 1, when such an arrangement is considered desirable. Other arrangements of contacts for other purposes may, of course, be provided as required. It will be evident that the construction shown provides great flexibility in the switching arrangements which may be carried out. A great variety of contact opening and closing arrangements, with or without intervening shielding may be assembled along the lines indicated.

Relays which are to be held closed after receiving a closing impulse may be provided with latches as illustrated at 118, Figures 6, 7 and 8. The latter shows also the trip mechanism comprising electromagnet 120, armature 121 and linkage 122 interconnecting the armature 121 and trip bar 119. Linkage 122 may take a variety of forms. As shown in Figure 9 it comprises a link and bell crank so arranged that bar 119 is momentarily lifted to trip the latches whenever the trip coil 120 is energized. Bar 119 is then allowed to drop again even though the relay is still energized. This permits any relay receiving an impulse to be closed and latched, while previously closed relays are released.

Figures 10 and 11 indicate arrangements whereby, contacts, as 123, for handling power circuits may be applied to the relays. If certain of the relays are to perform household functions such as lighting the furnace or operating an appliance, such construction may also be applied thereto. Such power contacts may be used also with any of the tuning relays to close the power circuit in place of using a separate contactor therefor. This construction may be used also to make a power circuit contactor from standard relay parts. Such a contactor may be provided with

interlock contacts similar to contacts 116, and a latch, similar to 118, if desired.

An electrical interlocking and latching system may be used in place of the mechanical latches illustrated by 118 and release bar 119 if desired. It will be apparent that a great variety of constructions may be applied to relays and tuning means of the type described.

Figures 13 and 14 outline arrangements for employing relays, as 124, similar to those widely used in telephone systems. Each set of contacts, as 125, may have a small separate magnet, as 126, or the contacts may be arranged two sets to each magnet with suitable shields between contacts when necessary. Tuning capacitors, as 127, or other circuit elements may be grouped in association with the relays. An alternative arrangement for a tuning capacitor is shown at 128. This has a worm nut 129, and worm 130 arranged for vernier adjustment and compact mounting.

Figure 15 shows a superheterodyne type of receiver having three circuits 131, 132 and 133 whose tuning is varied in order to select various channels. These circuits are radio frequency input circuit 131, frequency changer input 132 and oscillator input 133. The circuits may be tuned by adjustable capacitors which are connected by relay control as indicated and as described in detail with reference to numerals 32, 33—35, 36 etc. of Figure 1. Electrical control, latching and interlocking may be provided as indicated and discussed in connection with Figure 1.

Figure 16 indicates diagrammatically, further circuit arrangements which may be used in the combination there indicated or in other combinations. The first three tubes 134, 135 and 136 constitute the radio amplifier, frequency changer and oscillator of a superheterodyne receiver suitable for both short and long wave reception. For short wave reception, a wide range doublet antenna, or other suitable wave interceptor is connected through a suitable short wave circuit, as 137, to tube 134. Short wave frequency changer and oscillator circuits for tubes 135 and 136 are indicated at 138 and 139. For long wave reception, the antenna becomes a T type of aerial feeding long wave input circuits 140 for tube 134. Circuit 141 provides long wave input for tube 135 and circuit 142 for the oscillator 136. Additional input circuits adapted to whatever radio or wire line channels are to be used may be added and connected into the systems as required by suitable relays. Tube 143 serves the multiple purpose of intermediate frequency amplifier for superheterodyne reception, tuned radio frequency amplifier for high quality local reception, and carrier amplifier for wire line carrier reception. A sharply tuned intermediate frequency input transformer is indicated at 144 and a band pass transformer for high quality reception at 145. These may be tuned for the same or for different intermediate frequencies and additional transformers may be provided for additional characteristics if desired. Circuit 146 indicates a sharply tuned input circuit for use with a tuned radio frequency channel, either with separate aerial or with the same aerial as shown, wherein a suitable autotransformer 147 is employed. The circuit 148 may be a broadly tuned band pass input circuit for tuned radio frequency operation. Circuits 149 and 150, and others when desired may be constructed in accordance with my copending application 741,139, filed August 23, 1934, or in any other suitable manner. This applies also to circuits 149 and 150 used for applying wire line carrier

signals to tube 143 from line 150A. Any suitable coupling means and input system may be used. Additional amplifiers succeeding stage 143 may be provided as required, followed by suitable governor, compensator, demodulator and audio stages. These need not be discussed in detail here as it will be evident from the foregoing illustrative examples that practically any desired combination of circuits may be brought into play through suitable arrangements.

Figure 17 shows an example of relay control circuits utilizing a control clock in which the hour hand serves for both the timing and circuit routing functions. The hour hand 151 makes successive contact with the time busses, as 12, and these in turn route the circuit through interconnectors, as 13, to the station busses 1 to 10 inclusive. The relay coils indicated at 152 may be of a type held closed by continuous current therethrough eliminating the latches if desired, and the power supply circuits may be energized by a contactor 153 in the common return circuit of all relays. A reject button 154 and relay 155 are indicated to turn off the set by shunting the power supply relay coil 156. The reject button 154 opens a circuit shunting the operating coil 157 of the reject relay, 155, causing the latter to close and cut off the power supply by shunting coil 156. A resistor 158 supplies holding potential to 157 after the reject button again closes. Reject relay 155 opens whenever the current is momentarily interrupted, as by hour hand 151 dropping from one contact to another. It closes and cuts off the power supply only when reject button 154 is opened; at all other times, the potential 15 across resistor 158 is insufficient to close it. The potential is sufficient however, to hold it closed after being closed by operating button 154. A two way switch 159 permits a set of buttons, as 160, to be substituted for the clock control. These buttons are preferably of the type having a mechanical interlock which holds one button closed while releasing all others.

It will be evident that circuits having relays operated by impulses, as shown in Figure 1 may be applied to a clock of the type indicated in Figure 17, having only hour hand timing control by providing suitable interlocks and releases.

Figure 18 shows diagrammatically one form of circuit connections suitable for applying the multiple function control clock of my copending application, Serial No. 82,495, filed May 29, 1936, to an "all wave" radio receiver utilizing motors for operating the tuning and switching mechanism thereof. Outline 161 designates the clock control unit which may be similar to that shown in Figure 1, or like that of Figure 17 or one of the other forms outlined in the application just mentioned. Unit 161 may operate a tuning motor directly or via a set of relays as indicated at 162. Each relay shown at 162 operates two sets of contacts. One set controls a tuning mechanism 163 by means of a motor 164 and suitable reduction gears. In order to provide for precise tuning, a split spiral commutator, 165, 165A having a plurality of brushes as 166 arranged therearound is utilized. The brushes must, of course, be arranged to slide axially as the commutator is rotated so as to remain always in engagement with the spiral commutator. This commutator may be driven from an intermediate gear, as 167, and may make several revolutions for one revolution of the tuner 163. Connections from the two halves of the commutator may be made to a split field 168, 168A of motor 164. Additional con-

nections may be made to an armature or other winding, 169, combining with winding 168 to rotate the motor in either direction as determined by the commutator. A similar arrangement indicated at 170 may provide for rotating a switch to select a desired wave band. If the latter feature is omitted, the relays 162 may also be omitted and the tuner 163, motor 164, commutator 165, etc. connected directly to the control unit 161. 10 In some installations it may be desirable to provide several remote control stations in addition to the clock and the buttons thereon. The simplest form of this comprises one or more sets of push buttons connected in parallel with those in 15 the clock unit as shown at 171, Figure 19. Alternative programs may thus be selected without in any way interfering with future programs scheduled via the clock. When a parallel connected control such as this is employed, it may 20 be convenient to operate the volume and tone controls by means of small split field motors as illustrated at 172 and 173, Figure 19. Motor 173 may if desired operate a rheostat or other means for changing the response of the audio 25 amplifier and also operate variable band pass radio frequency circuits, as 175 in accordance with my copending application S. N. 741,139 of August 23, 1934. In Figure 19, numeral 176 outlines the "clock unit" with its clock and button 30 controls. Tone and volume controls 177 and 178 may be double throw key switches, normally open. A remote control station of which any number may be provided is indicated at 179. Each remote control station has a bank of 35 control buttons, as 171, a tone control 180 and a volume control 181.

An alternative to the arrangement shown, in Figure 19, is to provide a set of interlocked relays, similar to those shown in Figures 2 and 7, 40 for transferring the control from the clock unit to one or more auxiliary control stations. Each station may have a "master button" or other means of actuating the relay which transfers the control to that particular station. Details of this 45 suggestive alternative and others need not be discussed here.

It will be apparent to those skilled in the electrical and mechanical arts that my system possesses great flexibility and that it may take many forms and be applied to many purposes beyond those chosen for illustration herein. I do not limit myself to the forms shown but claim broadly as my invention the features of novelty and utility set forth in the claims appended hereto 50 and to my copending applications to which reference has been made.

I claim:

1. In combination, a communication receiver comprising a plurality of communication channel selecting means, a plurality of relays for operating said communication channel selecting means, a source of energy for operating said relays, and a control circuit for selectively directing the source of energy to correspondingly selected relays to energize the same, interlock means for holding closed any one of the relays

so selected and operated, means including a magnetically operated mechanical trip member for releasing the interlock when the new relay is selected and for opening all relays when the control circuit is routed via an "Off" position, a contactor operated with the relays for energizing the power circuits of the receiver when any communication channel relay is closed and an interlock operating with the relays for reducing the output of the receiver during operation of the 10 relays. 5

2. In combination, a communication receiver comprising a plurality of channel selecting means, a plurality of relays for operating said channel selecting means, a source of energy for operating said relays and a control circuit for selectively operating said relays, interlock means including a latch for holding closed any one of the relays selected and operated, means for releasing the interlock when a new relay is selected 20 and for opening all relays when the control circuit is routed through an "off" position, a contactor operated with the relays for energizing the power circuits of the receiver when any channel relay is closed, and an interlock operating 25 with the relays for reducing the output of the receiver during operation of the relays.

3. In combination, a communication receiver comprising a plurality of channel selecting means, a plurality of relays for operating said channel 30 selecting means, a source of energy for operating said relays, means for energizing a selected relay for operating a corresponding channel selecting means, interlock means for holding closed any one of the relays so selected and operated, 35 means common to all of said relays for releasing the interlock when a new relay is selected and for opening all relays when the control circuit is routed through an "off" position, with said interlock means acting immediately, a contactor operated with the relays for energizing the power 40 circuit of the receiver when any channel relay is closed, and an interlock operating with the relays for reducing the gain of the receiver during 45 operation of the relays.

4. A radio receiver tuning system including a plurality of electrical tuning means for connection to the tunable stages of a radio receiver circuit, a plurality of relay units corresponding in number to said tuning means for selectively connecting said tuning means into the receiver circuit, each of said relay units including a plurality of switches, movable means common to all of said switches and operatively connected therewith, an electromagnet unit including an armature connected with said movable means, interlock means for mechanically locking said armature in closed position, a single trip means operatively common to all of said relay units acting on said interlock means for opening all closed armatures, 50 means for closing a power circuit in the radio receiver when any relay unit is closed and means acting directly on at least one tuning stage in the receiver circuit for reducing the gain in such stage when any relay unit is opening or closing. 55

HAROLD F. ELLIOTT. 65
